UNITED STATES PATENT OFFICE.

THOMAS PODMORE, OF WILKES-BARRE, PENNSYLVANIA.

FIREPLACE DAMPER.

Application filed October 25, 1923. Serial No. 670,729.

To all whom it may concern:

Be it known that I, THOMAS PODMORE, a citizen of the United States, residing at Wilkes-Barre, in the county of Luzerne and State of Pennsylvania, have invented a new and useful Fireplace Damper, of which the following is a specification.

The present invention relates to chimney dampers, and more particularly dampers especially designed for use in connection with fireplace chimneys.

An important object of the invention is to provide novel means whereby the damper may be secured at the mouth of the chimney, eliminating the necessity of making alterations in the chimney construction to position the damper.

Another object of the invention is to provide means whereby the damper may be moved to a position out of the path of travel of the flames and heat passing into the chimney.

A still further object of the invention is the provision of a regulating device whereby the damper may be held in various positions of adjustment.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

Figure 1 is a sectional view through a chimney disclosing a damper constructed in accordance with the invention as positioned therein.

Figure 2 is an elevational view of the damper and its housing.

Figure 3 is a fragmental view disclosing the adjusting means.

Referring to the drawing in detail, the reference character 5 designates the mouth of a chimney adjacent to the fireplace, which is shown as relatively wide to accommodate the damper housing 6 which includes end sections 7, a forward section 8, and an inclined rear wall 9. Flange 10 is formed integral with the damper housing and pro-

vides means to restrict movement of the damper housing within the chimney 5 and at the same time affords a surface to be cemented or otherwise secured to the wall of the chimney.

The end sections 7 are formed with openings to receive the pintles 11 formed at the ends of the supporting bar 12 that supports the damper plate 13, the damper being secured to the supporting bar 12 by means of the bolts 14 shown as passing therethrough. This damper is relatively wide and is adapted to substantially close the damper housing to cut off the draft through the chimney when desired.

Secured to the damper 13 is an operating handle 15 that is secured by means of the rivet 16, the free ends of the handle being formed into a hook member 17 that may be engaged by a poker or suitable operating rod for moving the damper to its inactive position, to regulate the draft.

The operating handle 15 is secured to the damper 13 to permit of pivotal movement of the operating handle to allow the same to move laterally into engagement with the plate 18 that extends at an angle with respect to the section 9, the plate being disposed in a horizontal plane, and secured to flange 10.

Notches 19 are formed in one edge of the plate and present shoulders 20 to be engaged by the operating handle 15, when the operating handle is swung laterally to a position as indicated in dotted lines in Figure 2 of the drawing, whereby the damper 13 may be held in various positions of adjustment.

Due to the construction of the plate it will be obvious that the handle 15 may be moved to various positions of adjustment and hold the damper in various positions of adjustment for controlling the draft through the chimney.

I claim:

A damper including a body portion adapted to be fitted in a flue, a supporting bar having pintles at its ends, said body portion having openings to receive the pintles, a damper plate secured to the supporting bar to move therewith, an operating handle having pivotal connection with the damper plate to swing laterally with respect thereto, a plate having cut out portions, secured to the

body portion and extending into the flue, said cut out portions defining shoulders, said shoulders being various distances from one edge of the body portion, and said operating handle adapted to be moved to engage the shoulders for holding the damper plate in various positions of adjustment.

In testimony that I claim the foregoing as my own, I have hereto affixed my signature in the presence of two witnesses.

THOMAS PODMORE.

Witnesses:

IDA M. THOMAS,
WILLIAM PODMORE.
